UNITED STATES PATENT OFFICE

136,433

DESIGN FOR A SWEATER DRIER

Lillian J. Davis, Chicago, Ill.

Application May 10, 1943, Serial No. 110,175

Term of patent 14 years

To all whom it may concern:

Be it known that I, Lillian J. Davis, a citizen of the United States, residing at Chicago, in the county of Cook and State of Illinois, have invented a new, original, and ornamental Design for a Sweater Drier, of which the following is a specification, reference being had to the accompanying drawing, forming part thereof.

Fig. 1 is a plan view of a sweater drier, on a slightly reduced scale, showing my new design; Fig. 2 is a plan view of the sweater drier in Fig. 1, with one sleeve removed; and Fig. 3 is an edge view thereof.

I claim:

The ornamental design for a sweater drier, as shown.

LILLIAN J. DAVIS.
